US00D779579S

(12) **United States Design Patent** (10) **Patent No.:** **US D779,579 S**
Anari, III et al. (45) **Date of Patent:** **** Feb. 21, 2017**

(54) **CAMERA SUPPORT**

(71) Applicants: **Anthony F. Anari, III**, Sussex, NJ (US); **Ryan Paul Vosburg**, Riverdale, NJ (US); **Russell Van Zile, III**, Riverdale, NJ (US)

(72) Inventors: **Anthony F. Anari, III**, Sussex, NJ (US); **Ryan Paul Vosburg**, Riverdale, NJ (US); **Russell Van Zile, III**, Riverdale, NJ (US)

(73) Assignee: **AR2 PRODUCTS LLC**, Pompton Plains, NJ (US)

(**) Term: **14 Years**

(21) Appl. No.: **29/513,953**

(22) Filed: **Jan. 7, 2015**

(51) LOC (10) Cl. **16-05**

(52) U.S. Cl.

USPC **D16/242**

(58) **Field of Classification Search**

CLAIM

We claim the ornamental design for a camera support, as shown and described above.

DESCRIPTION

FIG. 1 is a front perspective view of the present invention, a camera support;

FIG. 2 is a front elevational view of the camera support seen in FIG. 1;

FIG. 3 is a rear elevational view of the camera support seen in FIG. 1;

FIG. 4 is a right side elevational view of the camera support seen in FIG. 1;

FIG. 5 is a left side elevational view of the camera support seen in FIG. 1;

FIG. 6 is a top plan view of the camera support seen in FIG. 1; and,

FIG. 7 is a bottom plan view of the camera support seen in FIG. 1.

The broken lines in each of the figures are for environmental purposes only and form no part of the claimed design.
